United States Patent

Dec. 240,521
Patented July 13, 1976

240,521

UTILITY BUILDING OR SIMILAR CONSTRUCTION

James T. Cribben, Mechanicsburg, Pa., assignor to
Capitol Products Corporation, Mechanicsburg, Pa.

Filed May 21, 1973, Ser. No. 362,020

Term of patent 14 years

Int. Cl. D25—03

U.S. Cl. D25—22

FIG. 1.

FIG. 2.

FIG. 3.

FIG. 4.

FIG. 1 is a perspective view of a utility building or similar construction embodying my new design;

FIG. 2 is a front view thereof with the doors in a closed position;

FIG. 3 is a side view with the doors in a closed position; and

FIG. 4 is a top view thereof with the doors in a closed position.

The rear of the building is plain and unornamented.

I claim:

The ornamental design for a utility building or similar construction, substantially as shown and described.
